UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,356,181.

Specification of Letters Patent. Patented Oct. 19, 1920.

Application filed May 21, 1919. Serial No. 298,624.

To all whom it may concern:

Be it known that I, RAY S. WILBUR, a citizen of the United States, residing at Lyndhurst, in the county of Bergen, State 5 of New Jersey, have invented certain new and useful Improvements in Telephone-Exchange Systems, of which the following is a full, clear, concise, and exact description.

This invention relates to telephone 10 exchange systems, and more particularly to such systems of the central energy type in which the source of ringing current is automatically connected to and disconnected from a telephone line.

15 An object of this invention is the production of improved signaling means for systems of this character in which the signal control apparatus functions independently of the length of the telephone lines to which 20 signaling current may be connected.

In attaining this object of the present invention, there is provided at the central office, means for connecting the source of 25 signaling current with a telephone line, a relay energized by current from the source for maintaining the source connected therewith and a relay energized in response to the subsequent closure of the telephone line for disconnecting the source therefrom.

30 A more complete understanding of the invention may be had from the following description taken in conjunction with the accompanying drawing which forms a part thereof.

35 Figure 1 shows a trunk circuit illustrating one embodiment of the invention; and Fig. 2 illustrates a second embodiment of the invention as applied to a cord circuit.

Referring now to the drawing, there is 40 shown in Fig. 1 a trunk circuit A extending from a switchboard X to a switchboard Y. The portion of the apparatus to the left of the dotted line 2-2 is associated with the switchboard at X, while that to the right 45 thereof is associated with the switchboard at Y. In Fig. 2 there is shown the calling end of a cord circuit D together with the telephone line E which terminates at the central office. It is thought that the operation 50 of the system will be more clearly understood after considering the following description.

Let it be assumed that the operator at Y has assigned the trunk A to be used in completing a connection with the telephone line 55 C and that the operator at X has inserted plug 5 of a cord circuit within jack 6. Relay 7 thereupon operates over a circuit extending from battery (not shown) in the cord circuit at position X through the ring 60 contacts of the plug 5 and the jack 6, winding 8 of repeating coil 9, the right-hand winding of relay 7, winding 10 of repeating coil 9, tip contacts of the jack 6 and the plug 5 and over the tip conductor of the connected cord circuit to ground. Relay 7 in operating causes the operation of relay 11 over a circuit extending from battery through the winding of relay 11 and the contact of relay 7 to ground. The operation 70 of relay 11 causes the illumination of supervisory lamp 12 over a circuit extending from battery through the lamp 12, right-hand alternate contact of relay 11 and normal contact of relay 13 to ground, which serves 75 as an indication to the operator at A that connection has been completed with the assigned trunk.

The operator, having been advised that connection is desired with the line of subscriber C, inserts plug 14 of the trunk circuit A into jack 15 of the telephone line, causing the operation of relay 13 and cut-off relay 16 over a circuit from battery through the winding of relay 13, sleeve contacts of the plug 14 and the jack 15 and the winding of relay 16 to ground. The cut-off relay 16 in operating disconnects the line relay 17 from the line wires. Relay 13, in operating, causes the extinguishment of the lamp 12 by the opening of its normal contact. The operation of relay 13 also causes the operation of ringing relay 19 over a circuit from battery through the winding of ringing relay 19, the normal contact of relay 20, left-hand alternate contact of relay 11 and the alternate contact of relay 13 to ground. Relay 19 in operating causes the energization of relay 20 over a circuit from battery through the winding of relay 20, an upper alternate contact of ringing relay 19, normal contact of relay 20, left-hand alternate contact of relay 21 and the alternate contact of relay 13 to ground. Relay 20 in

operating locks up through its alternate contact and transfers the holding circuit of relay 19 to the normal contact 24 of relay 21.

The operation of ringing relay 19 connects

- 5 a source of ringing current to the called for line over a circuit extending from the source thereof through a lower alternate contact of ringing relay 19, winding of relay 22, condenser 23, an upper alternate
- 10 contact of ringing relay 19, tip contacts of the plug 14 and the jack 15, out over one side of the line, through the usual call bell at the station C, back over the other side of the line, ring contacts of the jack 15 and the
- 15 plug 14, and a lower alternate contact of ringing relay 19 to ground. Condenser 23 prevents the flow of direct current through the winding of relay 22. Ringing current also traverses the winding of relay 21,
- 20 which, with respect to the source of ringing current, is connected in parallel with the line. The armatures of the relays 21 and 22 are connected together and are held in their normal unactuated position by means
- 25 of a retractile spring 44. The adjustment of these connected armatures with respect to the pole faces of the relays 21 and 22 is such that when the windings of both are traversed by ringing current only, as before
- 30 the closure of the switchhook contacts at the called station, the relay 22 exerts a much greater pull upon the armatures than is exerted by the relay 21. However, when the winding of relay 21 is also traversed by direct current, the relay 21 then exerts a greater
- 35 pull upon the armatures than is exerted by the realy 22.

The party at station C in answering the call by removing the receiver from the

- 40 switchhook closes the contacts thereof, thereby causing the operation of relay 21 over a circuit from battery through the winding of relay 21, an upper alternate contact of relay 19, tip contacts of the plug 14 and the jack 15, through the contacts of the switchhook at station C, ring contacts of the jack 15 and the plug 14, and a lower alternate contact of relay 19 to ground. Relay 21 is so designed that when the energizing
- 45 circuit therefor is completed it posseses sufficient magnetizing force or pull to overcome that exerted by relay 22 on the rigidly connected armatures. The operation of relay 21 thereby opens its normally closed contact
- 50 24 which opens the holding circuit for ringing relay 19, causing the release thereof and the disconnection of the ringing current from the line.

Upon the release of ringing relay 19, su-

- 60 pervisory relay 25 operates over a circuit from battery through the winding of relay 25, lower normal contact of relay 19, ring contacts of the plug 14 and the jack 15, out over one side of the line, contacts of the
- 65 switchhook, back over the other side of the

line, tip contacts of the jack 15 and the plug 14 and an upper normal contact of relay 19 to ground. Relay 25 in operating connects the low resistance left-hand winding of relay 7 in parallel with the high resist- 70 ance right-hand winding thereof, thereby reducing the resistance in circuit with the calling supervisory relay (not shown) of the connected cord circuit premitting the operation of this relay. The operation of 75 this supervisory relay extinguishes the supervisory lamp controlled thereby, which is an indication to the operator that the called party has responded.

It is thereby evident from the above de- 80 scription that the disconnection of ringing current from the line is controlled entirely through the contacts of the switchhook. The ringing current will, however, be connected to the line as long as such contacts are main- 85 tained open, since the armatures controlled by relays 21 and 22 are rigidly connected together, thereby maintaining the energizing circuit of the ringing relay 19 closed until a path for direct current through the 90 winding of relay 21 is established, which is not effective until the subscriber answers. Since ringing current traverses the windings of both of the relays 21 and 22, it will be seen that variations in length of line will 95 have but little effect upon both relays and the increase of current through the winding of relay 21, due to an increase of impedance when the line is lengthened will not be suffi- 100 cient to cause it to exert a greater pull on the armatures than is exerted by relay 22 while ringing current only is traversing the windings of both. Therefore, the possibility of premature disconnection of ringing current from the line is eliminated.

105 Referring to Fig. 2, there is shown a portion of a long line circuit terminating in the jack 26, with which the cord circuit D (only a portion of which is shown) is adapted to be connected. The cord circuit D is 110 equipped for automatic ringing while the long line circuit is provided with improved means for maintaining the ringing current connected thereto, as long as the line is open and disconnecting the same upon the closure 115 of the line.

120 Referring to the operation of the system shown in Fig. 2, the insertion of the plug 27 of the cord circuit D into the jack 26 of the line E causes the operation of relay 28 and illumination of the lamp 29 over a circuit from battery through the lamp 29, winding of relay 28, sleeve contacts of the plug 27 and the jack 26 to ground. The operation of relay 28 causes the energization 125 of ringing relay 31 over a circuit from bat- tery through resistance 30, winding of ring- ing relay 31, normal contacts of relays 32 and 33, and the contact of relay 28 to ground. Ringing relay 31 upon being en- 130

ergized connects a source of ringing current to the line over a circuit from the source through the winding of tripping relay 33, lower alternate contact of ringing relay 31, 5 ring contacts of the plug 27 and the jack 26, out over line wire 42, through the call bell at the station (not shown), back over line wire 43, tip contacts of the jack 26 and the plug 27 and the upper alternate contact of 10 relay 31 to ground. Ringing current also traverses the windings of relays 35 and 37, but the adjustment of the armatures thereof, which are rigidly connected together, with respect to the pole faces of these relays 15 is such that when ringing current traverses the windings of both relays before the closure of the telephone line, relay 35 exerts a greater pull upon the armatures than is exerted by relay 37. The rigidly connected 20 armatures are held in their normal unactuated position by means of a retractile spring 45. However, upon the closure of the telephone line, as when the receiver is removed from its switchhook, a path for direct current is established including the windings of 25 relay 37, which will thereupon exert a much greater pull on the rigidly connected armatures than is exerted by relay 35.

The called subscriber in responding to the 30 operation of the call bell removes the receiver from the switchhook establishing the path for direct current, including the windings of relay 37. Relay 37 now exerts a much greater pull on the rigidly connected 35 armatures than is exerted by relay 35, thereby closing contact 38 which connects the impedance coil 36 in bridge of the telephone line.

The connection of the impedance coil 36 40 in bridge of the telephone line causes the operation of the tripping relay 33 which removes the short circuit from about the winding of relay 32. Relay 32 thereupon operates opening another contact in the normal short circuit of its own winding, and 45 establishing at its alternate contact a short circuit for the winding of ringing relay 31, causing the release thereof and the disconnection of the source of ringing current from the line. Supervisory relay 40 now 50 operates over a circuit from battery through the lower right-hand winding of repeating coil 41, winding of supervisory relay 40, lower normal contact of ringing relay 31, 55 ring contacts of the plug 27 and the jack 26, impedance coil 36, contact 38, tip contacts of the jack 26 and the plug 27, the upper normal contact of relay 31 and the upper right-hand winding of the repeating coil 41 60 to ground. Supervisory relay 40 in operating connects resistance 30 in shunt of the supervisory lamp 29, which is thereby extinguished.

What is claimed is:

65 1. A telephone exchange system compris-

ing a telephone line, a source of signaling current, a link circuit, means in the link circuit responsive to the connection thereof with the telephone line for connecting the source of signaling current to the line, and 70 further means operated by current from said source for maintaining the source of signaling current connected with the line until the closure thereof.

2. A telephone exchange system comprising 75 a telephone line, a source of signaling current, a link circuit, a ringing relay in the link circuit responsive to the connection thereof with the telephone line for connecting said source of signaling current to the 80 line, and a relay initially energized by current from said source for maintaining the source of signaling current connected with the line until the closure thereof.

3. A telephone exchange system comprising 85 a telephone line, a link circuit, a source of ringing current, a ringing relay energized upon the connection of the link circuit with the line to connect the source of ringing current with the line, a relay energized 90 by ringing current to maintain the ringing relay energized, and a third relay energized upon the removal of the receiver from its switchhook to cause the release of the ringing relay.

4. A telephone exchange system comprising 95 a telephone line, a link circuit, a source of ringing current, a ringing relay in the link circuit for connecting ringing current to the line, an impedance coil, a relay energized by current from said source to maintain the ringing relay energized, and means operative upon the closure of the telephone line to connect said impedance coil in bridge 100 of the telephone line, thereby causing the release of the ringing relay to disconnect the source of ringing current from the line.

5. A telephone exchange system comprising 105 a telephone line, a link circuit, a source of signaling current, a relay in the link circuit for connecting the source of signaling current with the line, means operated by current from said source to maintain the source of signaling current connected to the telephone line while open, and a second 110 means operative upon the closure of the telephone line to cause the release of the ringing relay to disconnect the source of signaling current from the line.

6. A telephone exchange system comprising 115 a telephone line, a link circuit, a source of signaling current, a relay in the link circuit for connecting said source of signaling current with the line, a relay energized 120 by current from said source upon the connection of the source of signaling current with the line to maintain said source of signaling current connected thereto until the closure of the telephone line, and a relay 125 energized upon the closure of the telephone 130

line to cause the release of said first mentioned relay to disconnect the source of signaling current from the line.

7. In a telephone exchange system, in combination, a telephone line, a source of signaling current, means for connecting the source of signaling current with the telephone line, a relay energized by current

from said source for maintaining the source connected with the telephone line, and a relay energized in response to the closure of the telephone line for causing the disconnection of the source therefrom. 10

In witness whereof, I hereunto subscribe my name this 15th day of May A. D., 1919. 15

RAY S. WILBUR.
